UNITED STATES PATENT OFFICE.

KARL STIMÉCZ, OF CINCINNATI, OHIO.

DESIGN FOR A COMBINATION-TOOL.

46,890.

Specification for Design.

Patented Jan. 26, 1915.

Application filed August 31, 1914. Serial No. 859,550. Term of patent 7 years.

To all whom it may concern:

Be it known that I, KARL STIMÉCZ, a subject of the Emperor of Germany, residing at Cincinnati, in the county of Hamilton and State of Ohio, have invented a new, original, and ornamental Design for a Combination-Tool, of which the following is a specification, reference being had to the accompanying drawings, forming part thereof.

Figure 1 is a plan and Fig. 2 is a side elevation, showing my new design.

I claim:—

The ornamental design for combination tool, as shown.

KARL STIMÉCZ.

Witnesses:

FRANZ SVÉCKERT,
JOHANN FROHMAN.
